UNITED STATES PATENT OFFICE.

ANDREW J. CARMICHAEL AND ORESTE BALZANO, OF NEW HAVEN, CONNECTICUT, ASSIGNEES TO THE GREIST MANUFACTURING COMPANY, A CORPORATION OF CONNECTICUT.

SEWING-MACHINE HEMMER.

Application filed January 31, 1927. Serial No. 164,838.

This invention relates to sewing machine presser foot hemmers, and has for its object to provide a hemmer of this kind which consists of three sheet metal parts, so that it may 5 be manufactured at little cost by stamping, and without requiring milling of any consequence. To this end this improved hemmer consists of three sheet metal parts, comprising a presser foot and its shank, a thin metal 10 plate part secured to the foot and having a tongue and opening, and a second thin metal plate part or scroll portion loosely surrounding the said tongue, all as will hereinafter more fully appear.

15 In the accompanying drawing Fig. 1 is a plan view, on an enlarged scale, of the improved presser foot hemmer. Figs. 2 and 3 are side and bottom views, respectively, of the same. Fig. 4 is a front end view of the same 20 looking from the bottom of Fig. 1, and Fig. 5 is a detail perspective view of one of the hemmer plate parts.

Referring to the drawing, 12 denotes a sheet metal presser foot having a shank 13 25 which is forked for attachment to the presser bar of the sewing machine. Secured to the top portion of the presser foot is a hemmer plate part 14 having a tongue 15 extending into an opening 16 in said hemmer plate part, 30 said tongue being bent slightly downward. Attached to the forwardly extending toe portion of the presser foot is a second hemmer plate part 17 having an upwardly bent portion 18 carrying a rearwardly extending and 35 downwardly bent scroll finger part 19 loosely surrounding the tongue 15. The sheet metal plates 14 and 17 are preferably of much thinner material than the sheet metal presser foot and are preferably attached to the latter by 40 rivets 20, as more clearly shown in Fig. 1.

From the foregoing it will be apparent that the presser foot consisting of the three sheet metal parts referred to may be manu-

factured at little cost by stamping, the only milling required in completing the presser 45 foot hemmer being in the formation of the upwardly inclined groove 21 formed in the bottom of the presser foot rearward of the hemmer parts 15 and 19.

Having thus described our invention, we 50 claim and desire to secure by Letters Patent:

1. A presser foot hemmer consisting of three sheet metal parts comprising a presser foot having a shank and a forwardly extending toe portion, a sheet metal hemmer part 55 attached to the top of said presser-foot and having a tongue and an opening into which said tongue extends, and a second sheet metal hemmer part attached to the top of said forwardly extending toe portion of the presser 60 foot and having an upwardly inclined part carrying a rearwardly and downwardly extending scroll finger extending over and loosely surrounding the said tongue, said presser foot having a groove in its bottom 65 rearward of said tongue and finger.

2. A presser foot hemmer consisting of three sheet metal parts comprising a presser foot having a shank and a forwardly extending toe portion, a sheet metal hemmer part 70 attached to the top of said presser foot and having a tongue and an opening into which said tongue extends, and a second sheet metal hemmer part attached to the top of said forwardly extending toe portion of the presser 75 foot and having an upwardly inclined part carrying a rearwardly and downwardly extending scroll finger extending over and loosely surrounding the said tongue, the said hemmer parts being of much thinner sheet 80 metal than the presser foot portion of the hemmer.

In testimony whereof we affix our signatures.

ANDREW J. CARMICHAEL.
ORESTE BALZANO.
